UNITED STATES PATENT OFFICE.

CLARK J. SMITH, OF OTTUMWA, IOWA.

PNEUMATIC ROCK-DRILL.

1,086,625.

Specification of Letters Patent. Patented Feb. 10, 1914.

Application filed April 7, 1913. Serial No. 759,538.

To all whom it may concern:

Be it known that I, CLARK J. SMITH, residing at Ottumwa, in the county of Wapello and State of Iowa, have invented certain new and useful Improvements in Pneumatic Rock-Drills, of which the following is a specification.

This invention, which relates to improvements in rock drills, is more especially in the nature of a pneumatically actuated rotating attachment for pneumatic drills of the hammer type and more especially adapted for drilling coal rock and any hard mining substance.

In pneumatic rock drilling machines now in general use, where a reciprocating hammer piston, by rapidly successive blows, drives the drill bit farther into the substance being drilled, constant turning of the drill is necessary so that the cutting or penetrating portions on the end of the drill do not strike on the same indentations, which usually causes either a poor cutting or drilling or none at all.

My invention primarily seeks to provide certain improvements in rock drills of the general type stated of a simple and practical construction and in which the parts are coöperatively arranged and especially designed for obviating the usual extra attention of turning the bit by hand and with that and other objects in view my invention consists of the peculiar combination and novel arrangement of the parts, hereinafter fully described, specifically pointed out in the appended claims and illustrated in the accompanying drawings, in which:

Figure 1 is a longitudinal section, partly in elevation, of a pneumatic rock drill hammer showing my appliance attached thereto. Fig. 2 is an enlarged section on line 2—2 on Fig. 1. Fig. 3 is a view similar to Fig. 2, showing the parts in a different position. Fig. 4 is a section on line 4—4 on Fig. 3. Fig. 5 is a perspective view partly in section of the reciprocating air valve. Fig. 6 is a perspective of the pawl carrying and actuating block piston.

In the practical application of my present invention my improved attachments are

adapted for being mounted upon and combined with a hand machine in which is included a pneumatically actuated driving member or hammer, such a general type of machine being shown in the accompanying drawings in which *a* designates the handle that carries the casing *b*, in which is located a pneumatic hammer or plunger *c* of any approved type, the front end of the said casing having the usual passage *d* for the butt end of the drill *e*.

Referring now more particularly to my improved attachments, the same includes a main frame 1, that is attached to and is mounted on the front end of the casing *b* and disposed transversely thereof whereby to bring a forwardly extended apertured hub portion 15, of the said frame, in longitudinal alinement with the drill shank passage *d* in the casing *b*. The framing 1 also includes a cylinder 16, the opposite ends of which are formed with axial sockets 17—17 for receiving the opposite ends of a shiftable valve 3 on which is loosely mounted a piston 2, provided with a central annular groove 20, for receiving the projecting lug 60 of the shiftable or ratchet block 6, presently again referred to.

17^a designates a main inlet for the working fluid, and the same is located centrally over the working cylinder and it communicates with the opposite ends of the said cylinder through the fluid passages 18.

Valve 3, before referred to, is in the nature of a central shaft for the piston, its opposite ends projecting into the sockets at the opposite ends of the working cylinder and each of the said ends has an inlet 30—30 that connects through the ports or channels 31 with the exhaust ports 4—4^a in the opposite ends of the cylinder.

Valve 3 at each end has an annular fluid passage 33 and each of the passages 33 connects with a longitudinal fluid passage 34—34, that extends over nearly to the other end of the valve and the end of each of the passages 34 terminates in a radial outlet 35 that opens into the working cylinder or chamber, as is best shown in Fig. 2 of the drawing, by reference to which it will be

also seen each end of the valve has another annular groove 36—36 that forms passages for the fluid passing from the main inlet to and through the lateral fluid passages to the working cylinder under the proper adjustments of the valve.

By reason of the peculiar construction and arrangement of the parts constituting the working cylinder and piston, it will be 10 readily apparent by referring to Figs. 1, 2 and 3, that when the piston has traveled to the position shown in Fig. 2, valve port 4^a opens which allows the fluid to pass to the right hand end of the valve 3, (see Fig. 2) 15 to force the said valve 3 back to the position shown in the said Fig. 2, thereby bringing the fluid passage from the main inlet into open communication with the working cylinder at the right hand end of the piston 20 and the other end of the cylinder into open communication with the exhaust 5.

Both ends of the cylinder and the valve are alike and hence after the action just explained has taken place under the movements of the piston in one direction, a like action takes place at the other end by reason of the movement of the piston in the other direction.

Since the piston and the valve travel the 30 same way, it is evident that should there be any friction on the piston or the valve, it will assist in holding the valve open to its work.

For turning the drill, I prefer to use the ratchet mechanism shown and the same includes a ratchet sleeve or bushing 8 that turns in the hub of the main framing and in which the drill shank is slidably held.

The ratchet block 6 before referred to is reciprocably held in a socket 61 in the framing and it carries a drop-pawl 10 that engages the ratchet at one side, a second pawl 12 being also provided for engaging the ratchet at the same side, the latter pawl being pivotally mounted on a rocker lever 9 40 normally moved by a spring 13 to pull the pawl 12 back from the ratchet 8. One end of the lever 9 is projected in the path of movement of the ratchet block 6 and is so disposed that as the said block is carried 45 forwardly with the piston 2 (see arrow x) the said block engages the lever 9 and thereby throws the pawl 12 to turn the ratchet with the drill in the direction indicated by the arrow y, it being obvious from the drawing, that as the block 6 is moved in the other 50 direction its pawl 10 engages and moves the ratchet 8 in the same direction, the reciprocal movement of the block 6 under the reciprocal actions of the piston imparts 55 a continuous rotary travel to the drill.

To provide for a simple and expedient assembling of the valve and the piston, one end of the piston cylinder casing is plugged as at 40, and the plug held by a cross pin 41.

While for convenience of illustration I 65 have disclosed a complete embodiment of my invention, yet in this application I make no claim to the specific construction of fluid pressure motor, *per se*, as that forms the subject matter of a divisional application 70 filed May 29, 1913, Serial No. 770,586.

From the foregoing taken in connection with the drawings, the complete construction, the manner of operation and the advantages of my invention will be readily 75 understood by those skilled in the art to which it appertains.

What I claim is:

1. A chuck holder, a chuck rotatively mounted thereon, a rectilinearly reciprocating block, connections between the said block and chuck for imparting rotation to the said chuck as the block is reciprocated, and a fluid operated engine including a reciprocating piston connected with the said 85 block for reciprocating the same.

2. In combination with a chuck holder, and a chuck rotatably mounted in said holder, said chuck having a ratchet portion, of a reciprocating block mounted in said 90 holder, a pawl carried by said block for engaging said ratchet portion, and a second pawl device mounted in said holder for engaging said ratchet portion, and including a member adapted to be engaged by said block 95 when reciprocated to turn said chuck.

3. A chuck holder, a chuck rotatably mounted therein, said chuck including a ratchet portion, a block reciprocably mounted in said chuck holder, a pivoted dog in 100 said chuck holder, and a pawl carried by said dog for engaging said ratchet portion, said dog having a portion projecting into the path of movement of said block, whereby, as said block is moved in one direction said 105 dog is moved to turn said ratchet, and means for reciprocating said block.

4. A chuck holder, a chuck rotatably mounted therein, said chuck including a ratchet portion, a block reciprocably mounted in said chuck holder, a pivoted dog in said 110 chuck holder, and a pawl carried by said dog for engaging said ratchet portion, said dog having a portion projecting into the path of movement of said block, whereby, as said block is moved in one direction said 115 dog is moved to turn said ratchet, and means for reciprocating said block, a pawl carried by said block for engaging said ratchet to turn said ratchet as said block is moved in a direction opposite to that in which said dog is operated.

5. A chuck holder, a chuck rotatively mounted thereon including an annular ratchet member, a reciprocating block, connections between the said block and the chuck for imparting rotation to the said 125 chuck as the block is reciprocated, said con-

nections including a pawl carried by the block for engaging the ratchet member as the block moves in one direction, a rocker pawl for engaging the said ratchet member that is actuated by the said block as the block moves in the opposite direction, and a fluid operated engine including a reciprocat-

ing piston connected with the said block for reciprocating the same.
